UNITED STATES PATENT OFFICE.

WILLIAM NATHAN ELLIOTT, OF MEMPHIS, TENNESSEE.

SAWMILL LOG-TURNER.

SPECIFICATION forming part of Letters Patent No. 681,047, dated August 20, 1901.

Application filed March 6, 1901. Serial No. 50,013. (No model.)

To all whom it may concern:

Be it known that I, WILLIAM NATHAN ELLIOTT, residing at Memphis, in the county of Shelby and State of Tennessee, have made 5 certain new and useful Improvements in Saw-mill Log-Turners, of which the following is a specification.

My invention relates to certain improvements in steam log-turners of that class which 10 employ a toothed bar called a "nigger," and which, occupying a generally-vertical position, is made to rise and fall beneath the log and also to move laterally in horizontal direction as it operates on the log above and 15 serves to turn the same or transfer it from the log-deck to the sawmill-carriage.

My invention consists in the special means 20 for cushioning the nigger-bar against shock in its backward and forward thrust in a horizontal direction as it rises and falls beneath the log, as will be hereinafter fully described with reference to the drawings, in which—

Figure 1 is a vertical transverse section taken through the log-carriage and the log-deck, showing my devices in longitudinal section in proper relation to the coacting parts. Fig. 2 is a view showing the backward thrust of the nigger-bar, and Fig. 3 is an enlarged perspective view of the parts of my invention shown detached.

In the drawings, Fig. 1, S is the log-carriage.

D is the log-deck, down whose inclined rails or skids the log is delivered and on which it 35 is turned and transferred to the carriage S. B is the nigger-bar, which effects this turning and transfer of the log. It is arranged at the lower end of the deck, beside the carriage S, in a substantially vertical position 40 beneath the log and extends down to and connects with the steam-piston, (not shown,) which works it in the usual way. Said nigger-bar has, as usual, a roller r at its upper end and stout teeth t extending out from its 45 sides beyond its side plates. This nigger-bar plays vertically through a hollow cross-head A, which has along each side the flanges f and f', Fig. 3, which slide on parallel guide-ways F F, the flanges f being above and the flanges f' below the guides, so that the cross-head cannot be displaced or lifted from the 50 guides by the up-and-down movement of the

nigger-bar through the cross-head. The guides F F are made of angle-plates bolted to the upper edges of the parallel floor-timbers M M.

The cross-head A is formed with a slot u in front to accommodate the rise of the teeth t through the same and has shoulders E E in front and E' E' at the rear on the inner side 60 of its opening, which bear against or closely approach the side plates of the nigger-bar B at all times. These shoulders are curved in reverse directions, as shown, so as to permit the nigger-bar to assume an inclined position 65 through the cross-head, as is shown in dotted lines in Fig. 1 and in full lines in Fig. 2. To the rear end of the cross-head there is rigidly attached a rod R, which extends back between the floor-timbers M M and passes 70 freely through and is guided by a plate X, fixed crosswise in the two floor timbers M M and extending across from one to the other.

This plate has on the front side a short sleeve x to better guide the rod as it slides through 75 and reduce looseness from wear. On the rod R, on one side of the fixed plate X, there is a plate V, attached to the plate X by small rods v, and on the other side of the fixed plate X there is a collar-nut W, fixed to the end of the 80 rod. Between the plates V and X there is arranged a stationary helical spring H, and between the plate X and collar-nut W there is a similar spring I; but this spring moves with the rod and is not attached to plate X. The 85 rods v pass either outside or inside the spring H to hold it in true concentric position on the rod R. The rear end of the rod R is screw-threaded, and a jam-nut Y is turned on the same to a bearing against the collar-nut 90 W. Now when the nigger-bar rises and falls and also swings laterally in a horizontal direction these springs H and I cushion it against said horizontal thrust, so that there is no shock or impact whatever, for when 95 the nigger-bar swings back the cross-head A and rod R move with it and the cross-head striking-plate V compresses the spring H, and when the nigger-bar swings forward the cross-head A pulls on rod R and causes the 100 collar-nut to advance with spring I and strike against plate X with an elastic blow.

By means of the nut Y the rod R, cross-head A, and nigger-bar B may be adjusted

to or from the saw and its carriage, as may be desired.

I do not claim, broadly, the arrangement of the springs on the opposite sides of a fixed plate, as I am aware that this is old when combined with an elongated movable guide attached to a rod passing through said springs and plate. In this case, however, the nigger-bar as it moves in said guide strikes 10 against the end of the latter and has to overcome the inertia of the heavy movable guide before it feels the cushioning effect of the springs, which gives an objectionable hammering action. I am also aware that a log- 15 loading bar has been made to play through a hollow and sliding cross-head. I do not know, however, that these two features have ever been combined, and their combination produces the useful effect of cushioning the 20 nigger-bar and cross-head directly against the springs without having first to overcome the inertia of the heavy guides, which latter are made stationary in my invention.

Having thus described my invention, what 25 I claim as new, and desire to secure by Letters Patent, is—

1. A log-turning device comprising a vertically and horizontally moving "nigger-bar," a cross-head closely embracing the same, 30 stationary guides for controlling the movement of the cross-head, a rod connected to the cross-head, a fixed plate loosely supporting the other end of the rod, two coil-springs embracing the rod on opposite sides of the 35 fixed plate, and two bearings for the opposite ends of the springs as described.

2. In a log-turning device as described, a sliding closely-fitting cross-head for the "nig- 40

ger-bar" having a rod with two coil-springs on it, a fixed plate between said springs, two 45 end bearings for the opposite ends of the springs, and several rods *v* extending through the forward plate to the fixed plate to hold the plate and guide it on the rod substantially as shown and described. 45

3. The combination of the "nigger-bar" and its retaining cross-head, closely fitting the same, the attached rod with double-acting springs, said rod being screw-threaded and provided with adjusting-nuts for adjusting the "nigger-bar" to the saw substantially as described. 50

4. The combination with the "nigger-bar" having projecting teeth *t*; of a retaining cross-head having slot *u* and bearing- 55 shoulders *E E'* curved to permit the change in the inclination of the "nigger-bar" in the cross-head and still cause it to be closely held, and double-acting springs for rendering the cross-head cushioned in both directions substantially as described. 60

5. The combination with the "nigger-bar;" of a sliding cross-head embracing the "nigger-bar" and having a rod extended from said cross-head, a fixed plate through which 65 the rod freely slides, a stationary coil-spring with retaining-plate and rods connecting the same to the fixed plate, and a second coil-spring arranged on the opposite side of the fixed plate and sliding with the rod substan- 70 tially as described.

WILLIAM NATHAN ELLIOTT.
